UNITED STATES PATENT OFFICE

103,751

DESIGN FOR A TEXTILE FABRIC

Joseph L. Titelbaum, New York, N. Y.

Application February 20, 1937, Serial No. 67,760

Term of patent 3½ years

To all whom it may concern:

Be it known that I, Joseph L. Titelbaum, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The drawing shows substantially the complete design unit, which comprises a series of four medallion-like elements arranged in staggered relation, each alternate row being in inwardly inclined relation to the row in upwardly inclined relation, as shown.

I claim:

The ornamental design for a textile fabric, substantially as shown and described.

JOSEPH L. TITELBAUM.
